DRAFTSMAN

UNITED STATES PATENT OFFICE.

MAX EMIL DEJONGE, OF STAPLETON, NEW YORK.

ANTI-FOULING PAINT.

SPECIFICATION forming part of Letters Patent No. 441,290, dated November 25, 1890.

Application filed October 10, 1889. Serial No. 326,575. (No specimens.)

To all whom it may concern:

Be it known that I, MAX EMIL DEJONGE, a citizen of the United States of America, residing at Stapleton, Staten Island, county of 5 Richmond, and State of New York, have invented and discovered a new and useful Composition or Paint for Use upon Metal and Wood; and I do hereby declare that the following is a full, clear, and exact description 10 and specification of the same.

I am aware that other anti-fouling paints and compounds have been made and used previous to my present invention; but I am not aware that any such compound as hereininafter described and claimed by me as my 15 invention has ever, previous to my discovery thereof, been known or used.

My invention relates to a compound for preserving the surfaces of wood, metal, and 20 like materials from the corrosive action of the atmosphere, gases, or fluids, and also from the injurious attacks of insects, especially those which produce barnacles upon ships' bottoms. I call my invention "Metallic Anti-Fouling Composition."

My invention consists in the compound composed of certain elements, fully set forth in and claimed at the end of this schedule.

In order that persons skilled in the art may 30 understand, compound, and use my invention, I will proceed to disclose it.

My metallic compound or paint consists of finely-divided zinc suspended in a vehicle composed of colophony, shellac, and fusel-oil, 35 by means of which it is spread upon and caused to adhere to the surfaces of the metal or wood.

I mix the zinc-dust aforesaid with the solution of varnish in about the proportion of 40 one part zinc-dust to two parts of the solution of varnish and stir them well together and apply the resultant compound with a brush in the ordinary manner. This compound hardens under water, so that a ship 45 coated with it can be launched as soon as painted. In painting wood with this paint I

do not need to prepare the surface of the 50 would beforehand; but in painting metals I first clean and dry the surface and put on it a priming of anti-corrosive compound, and when this priming has dried firmly I then paint over this priming with my compound of zinc-dust mixed, as before described, with a solution of rosin varnish and shellac in about the proportions above named.

In placing my compound upon the market 55 for sale I pack the zinc-dust in cases separate from the rosin and shellac varnish. In other words, I put up the varnish in one can and the zinc-dust in another and assemble and mix them together for use as required. This is done because the paint vehicle of colophony, shellac, and fusel-oil when mixed with zinc-dust produces explosive gases. A chemical action 60 takes place which is advantageous in applying the compound to metal and wood, but which renders it dangerous to assemble the separate constituents in sealed vessels.

This compound may be mixed and put in cans ready for use by puncturing the cans to 65 allow the gases to escape; but I prefer to market the compound in separate cans, as specified above.

I have found in testing my metallic anti-fouling compound on ships' bottoms that it 70 absolutely prevents fouling.

I propose to use my compound for other purposes than those enumerated herein, which it is not necessary to mention here.

Having now fully described my invention 80 and the manner in which I have embodied it, what I claim as new, and desire to secure by Letters Patent, is—

An anti-fouling paint composed of zinc-dust suspended in a vehicle of a solution of 85 colophony and shellac in fusel-oil, substantially as set forth.

MAX EMIL DEJONGE.
